Hugh S. Wagner,
ATTORNEY.

UNITED STATES PATENT OFFICE.

CHARLES T. STEVENS AND EDWIN S. DELAPLANE, OF ST. LOUIS, MISSOURI, AS-SIGNORS, BY MESNE ASSIGNMENTS, TO ATHLETIC HEALTH CHAIR COMPANY, OF ST. LOUIS, MISSOURI, A CORPORATION OF MISSOURI.

EXERCISER.

Application filed November 27, 1922. Serial No. 603,568.

To all whom it may concern:

Be it known that we, CHARLES T. STEVENS and EDWIN S. DELAPLANE, citizens of the United States, residing at the city of St. Louis, in the State of Missouri, have invented certain new and useful Improvements in Exercisers, of which the following is a specification.

This invention is an improvement of the subject-matter of the patent of William E. Lauer for exerciser filed August 18, 1921, Patent 1,456,317. It is to be understood that the device herein shown and described can be used in the same manner as the device illustrated and described in the said Lauer patent, but that the construction herein shown and described embodies improvements thereover.

In the accompanying drawings forming part of this specification, in which like numbers of reference denote like parts wherever they occur,

Figure 1 is a side elevation of this device when arranged to be used as an exerciser; Figure 2 is a side elevation thereof when set up as a chair; Figure 3 is a rear elevation of such chair; and

Figure 4 is a detail of the extensible tilt-resisting part.

While useful for the purposes set forth in the said Lauer patent, this device is more or less in the way in small apartments, and in the plain form shown in the said Lauer patent, may be so unornamental as to be unwelcome in the ordinary living rooms of a home. The principal object of the present invention is to provide the Lauer apparatus with an ornamental form, so that it can be kept in any living room, and also so to construct that device that it will be useful as a chair when not in use as an exerciser.

Further features of invention are found in the necessary alteration of structure to accomplish the aforesaid purposes and in the addition of exerciser rings, the use of which is made possible with this device by reason of the addition to the Lauer device of the chair feature.

All the parts of this device are formed, shaped, and finished in such a manner as to constitute the same when set up as a chair a beautiful and ornamental piece of furniture

having all the appearance of a high-class chair, the alternative use of which can not be detected from a front view of the chair and which can hardly be suspected from a side view thereof and which can be clearly perceived only from a rear view or from seeing the device laid down as an exerciser in the manner shown in Figure 1.

The base 1 constitutes the chair back. The legs 2 extend therefrom and are preferably integral therewith.

As best seen in Figure 4, a groove 3 is formed in each side of each leg 2, thus forming a tenon 4, adapted to fit within a channel-iron 5 having flanges 6. The channelirons 5 are slidable on tenons 4 and thus form tilt-resisting extensions in the manner shown in Figure 1. When a person using this device as an exerciser is seated upon seat 25 and exercising with his toes, held by the toehold 7, he can bend his head back to the floor near the extensions 5 and return to an upright position without danger of tilting the base 1 in either direction.

For adjustment the toehold 7 will preferably be formed with tongue and buckle 8 or the like, the said toehold 7 being comprised preferably of a strap or band, which is removable after the device has been used as an exerciser, so that its appearance will not be marred when standing erect like a chair, as shown in Figures 2 and 3. For the same reason the holders 9 are placed upon the back of the chairback or base 1, so that they will be out of sight when the device is standing or to be used as a chair. The holders 9 are for the reception of the toehold 7.

The rings 10 and elastic or spring cords 11 are mounted by eyelets 12 on the back of the chairback or base 1, so as to be out of sight when not in use, the rings 10 being held by hooks 13. The rings 10 and cords 11 can be used when the chair is in the position shown in Figures 2 and 3 as an exercising pull cord apparatus or, if desired, can be used by the exerciser when the device is in the position shown in Figure 1.

The holders or irons 9 are in a part of the chairback 1, forming a countersink 14 relative to the knobs 15 and the projections 16. This enables the device to lie flat upon the floor as shown in Figure 1. There is a plurality of pairs of holders 9, so that toehold

7 can be adjusted in its position relative to the seat 6, that is to say for people having longer or shorter legs.

The seat 25 is formed with cleats 17 adapted to fit within a groove 18 either in the seat frame 19 or in the front of the legs 20, thus serving a double purpose. Grooves 21 of an ornamental character in the front of legs 20 allow seat 25 to be used and fixed thereon in the manner shown in Figure 1. Ornamental round 22 serves as a brace, and ornamental rounds 23 serve as braces in Figures 2 and 3 and as supports in Figure 1.

Having thus described this invention, we hereby reserve the benefit of all changes in form, arrangement, order, or use of parts; as it is evident that many minor changes may be made therein without departing from the spirit of this invention or the scope of the following claims.

We claim:

1. An exercising apparatus comprising a base convertible into a chairback, a seat support adapted to selectively hold a seat in planes transverse to each other, and extensible tilt-resisting means carried by the lower end of the chair back adapted for use when the device is laid on its base for use as an exercising apparatus.

2. An exercising apparatus embodying the construction of a chair having a back and slidable tilt-resisting means connected with the lower end of the chair back adapted for use when the device is laid on its base for use as an exercising apparatus.

3. An exercising apparatus embodying a base convertible into a chair back and slidable tilt-resisting means connected to the lower end of the chair back and extended therefrom when the chair back is horizontally positioned as the base of the exerciser, and a toe hold attached to said base adapted to function when the device is used as an exercising apparatus.

4. An exercising apparatus embodying a base convertible into a chair back, and a slidable tilt resisting means connected to the lower end of the chair back and extended therefrom when the chair back is horizontally positioned as the base of the exerciser, a toe hold attached to said base adapted to function when the device is used as an exercising apparatus and holders for the said toe hold mounted on the underneath side of said base.

5. An exercising apparatus embodying a base convertible into a chair back, and a slidable tilt resisting means connected to the lower end of the chair back and extended therefrom when the chair back is horizontally positioned as the base of the exerciser, a toe hold attached to said base adapted to function when the device is used as an exercising apparatus and holders for the said toe hold mounted on the underneath

side of said base, there being a countersunk portion in the said base in which the holders are located to permit flat engagement of the base with a floor support.

6. An exercising apparatus embodying a base convertible into a chair back and slidable tilt resisting means connected to the lower end of the chair back and extended therefrom when the chair back is horizontally positioned as the base of the exerciser, the said slidable tilt resisting means being in the form of a channel iron having in-turned flanges and tenons on the said base upon which the same are adapted to slide.

7. An exercising apparatus adapted to serve as a chair when standing vertical and as a horizontal exerciser when in the horizontal position and having in its front grooves and on the upper part of its seat-supporting frame other grooves and a seat adapted to fit into either set of grooves.

8. A combination chair and exerciser in which the chair back forms the base of the exerciser when the chair is laid on its back, and contains within it extensible tilt-resisting means adapted for use when the device is laid on its back as an exerciser.

9. A combination chair and exerciser in which the back of the chair is the base of the exerciser when the chair is laid on its back and extensible tilt-resisting means slidably associated with one end of the base of the exerciser adapted for use when the chair is laid on its back for use as an exerciser.

10. A combined chair and exercising apparatus including a base for the exercising apparatus constituting the back of the chair, a seat support and front legs cooperating with the back to support the chair in upright position, a seat, said seat support, front legs and seat being cooperatively constructed for selectively mounting the seat on the seat support or front legs when the device is positioned upright as a chair or the chair back is horizontally positioned as the base of the exercising apparatus.

11. A combined chair and exercising apparatus including a base for the exercising apparatus constituting the back of the chair, a seat support and front legs cooperating with the back to support the chair in upright position, a seat, said seat support, front legs and seat being cooperatively constructed for selectively mounting the seat on the seat support or front legs when the device is positioned upright as a chair or the chair back is horizontally positioned as the base of the exercising apparatus, and tilt resisting means slidably carried by the base adjacent the chair end thereof.

12. A combined chair and exercising apparatus including a base for the exercising apparatus constituting the back of the chair, a seat support and front legs cooperating with the back to support the chair in up-

right position, a seat, said seat support, front legs and seat being cooperatively constructed for selectively mounting the seat on the seat support or front legs when the device is positioned upright as a chair or the chair back is horizontally positioned as the base of the exercising apparatus, tilt resisting means slidably carried by the base adjacent the chair end thereof, said base having cutaway portions on its lower side ¹⁰ and a toehold secured at its ends in the cutaway portions of the base.

In testimony whereof we hereunto affix our signatures.

CHARLES T. STEVENS.
EDWIN S. DELAPLANE.
